[57] CLAIM

The ornamental design for a vehicle windshield wiper unit, as shown and described.

DESCRIPTION

FIG. 1 is a side elevational view of a vehicle windshield wiper unit showing our new design;

FIG. 2 is an elevational view of the opposite side thereof;

FIG. 3 is a top plan view thereof; and

FIG. 4 is an enlarged end elevational view, the opposite end being a mirror image thereof;

FIG. 5 is a perspective view as seen from the top and that side shown in FIG. 2; and

FIG. 6 is a perspective view as seen from the top and opposite side thereof.

FIG-5

U.S. Patent

Apr. 24, 1990

Sheet 3 of 3
